UNITED STATES PATENT OFFICE.

LIONEL H. MOISE, OF SAN FRANCISCO, CALIFORNIA.

FRUIT AND VEGETABLE PRESERVING APPARATUS.

SPECIFICATION forming part of Letters Patent No. 325,954, dated September 8, 1885.

Application filed September 19, 1884. (No model.)

To all whom it may concern:

Be it known that I, LIONEL H. MOISE, a citizen of the United States, residing in the city and county of San Francisco, State of California, have invented certain new and useful Improvements in Fruit and Vegetable Preserving Apparatus; and I do hereby declare that the following is a full, clear, and exact description of my said invention, reference being had to the drawings that accompany and form a part of this specification.

My invention relates to machines or apparatus for canning, bottling, or putting up fruit, vegetables, and other perishable matter in sealed receptacles to preserve them for future use; and it consists in certain construction and combination of parts for producing a machine or apparatus having several advantages and improved features in respect of simplicity, general efficiency, ease of handling and operating, and cheapness of manufacture.

The following description fully explains the nature of these improvements over machines and apparatus heretofore used and the manner in which I proceed to construct an apparatus in accordance therewith.

Referring to the accompanying drawings by figures and letters, Figure 1 is an elevation of an apparatus constructed for general family use, or of suitable capacity for farmers and fruit-growers on a small scale. Fig. 2 is an end view of Fig. 1. Fig. 3 is a plan of the apparatus with the top removed. Fig. 4 illustrates on a smaller scale a style of apparatus of increased capacity produced for factory use.

I construct a case or close steamer-like vessel of suitable size and material, depending on the capacity of the apparatus to be produced, and in two parts or sections, of which the lower one, A, is the body, bottom, or stationary part, and the upper one, A*, forms the removable top, head, or cover. Within the stationary part is placed a level platform or surface, B, set on a support, b, projecting from the sides of the case to form a shelf or floor over the space below. This surface is formed in a simple and non-expensive manner from a metal plate with perforations or openings to permit passage and circulation of the steam from the space below it up into the upper compartment, and is provided with a number

of shallow rings or sockets, C, arranged in rows and suitably spaced to accommodate as many jars or receptacles as practicable. Each ring forms a holder, confining the jar in place upon the platform and regulating the space between it and its adjacent jars.

The construction I prefer to employ is that of an open ring secured at one end portion to the perforated floor, and having the other end portion detached, so that it can spring in or out to change the diameter, and thus adjust itself to the jar. This construction affords a firmly-holding socket, and is of considerable advantage in cases where the supporting-platform is adapted to be lifted out from the case with a load of jars; but in operating less extensively, and where economy of time is not a desideratum, the jars can be lifted out separately by hand, and then the supporting-plate does not require to be removable, and the sockets can be made of fixed rings of such size that they will accommodate any variation in sizes of the jars.

This supporting-surface B is set close up to the line of the rim or top edge of the lower or stationary part of the case, or at such point that the jars or receptacles when set in place will stand above the edge or rim of and will extend into the chamber or space formed by the upper removable part when it is brought down into place.

By this construction of case the jars are left exposed and standing out of the steam-space when the top is lifted, and the act of raising up this deep cover at the end of each operation quickly carries away the steam from the jars, and thereby permits instant handling to remove them from the holders.

This feature is of great advantage in affording a ready unloading of the apparatus and a rapid refilling, for the body of steam and vapor is allowed to ascend and leave the jars free, and its removal is likewise accelerated both by the form of the top or upper part and by its movement upward. This removable part of the case is fitted inside the rim of the lower stationary part, and its edge sets into the channel or recess d all around the margin of the perforated bottom. This forms a joint sufficiently steam-tight all around the cover.

In a large apparatus, where the weight of

the top A would be considerable, I provide a chain and tackle for conveniently raising and moving it, and in such case the same means could be utilized for lifting up the perforated 5 plate and removing the whole charge of jars at once, after the steaming operation, by simply attaching the lifting-chains to rings or eyes provided at the four corners of the plate.

The operation of this apparatus is intended 10 to be carried on either with steam directly supplied from a boiler or generator, or else by producing the steam from a body of water in the lower part of the case, the heat being obtained from a furnace or stove on which the 15 apparatus is placed.

In carrying on operations extensively, as in 20 factories and canning establishments, I would construct the apparatus substantially as represented in Fig. 4 of the drawings, with connection of the stationary part of the case with a steam-supply through a suitable pipe, P, and a discharge, q, to carry off the water of condensation. The top or removable part, being 25 of considerable size, would be handled by a device something like a crane with a hoisting-tackle, as represented, such as could readily be devised by a mechanic. The steam-inlet would be provided with a deflector plate, p, to keep the jars at and nearest the inlet from 30 receiving the direct force of the incoming steam.

A machine of smaller capacity would generate its own steam, being supplied with water, as required, through the top by means of 35 a pipe or hose; or, if a permanent fixture, it could be connected with a water-supply by a pipe having a shut-off cock.

On the case I provide a steam-outlet, R, controlled by a valve, and also a steam-gage, S, 40 for regulating the pressure and heat during operation.

Having thus fully described my invention, what I claim, and desire to secure by Letters Patent, is—

1. The combination, with the two-part steam- 45 ing case or receptacle A A*, of which the parts or sections are separable on a substantially horizontal line and the one removable from the other, of the perforated floor or supporting-surface B, provided with sockets C, and 50 placed within one of said sections in such position with respect to the line of separation that when the parts or sections are separated the jars are exposed outside of the compartment for ready handling and removing, substantially as hereinbefore described.

2. The herein-described machine or apparatus for steaming and otherwise treating fruit and like matter in close receptacles to preserve the same for future use, consisting of the 60 stationary part or chamber A, having a platform or supporting-surface situated over the steam-generating space of said chamber and in close relation to the top edge or rim of said chamber, and the removable upper part or 65 chamber, A*, adapted to fit over and inclose the jars when placed on the supporting-surface, and when removed to expose the jars or receptacles to the atmosphere and insure their speedy cooling and the speedy disappearance 70 of the steam and vapor, suitable connection of said apparatus being made with a steam-supply or with a heating-furnace.

3. The combination, with the stationary case 75 A, having the perforated supporting-surface B, with jar-holders, the removable top or upper part, A*, with steam-outlet R and steam-gage S, and the channel or space d in the stationary part around the margin, of the perforated support to receive the rim of the removable part of the case, substantially as described.
